(57) **CLAIM**

The ornamental design for a roofing support system, as shown and described.

DESCRIPTION

FIG. 1 is an exploded perspective view of an embodiment of a roofing support system comprising an upper core member, and a base member/lower cover layer member, in a detached or unassembled condition;

FIG. 2 is a perspective view of the embodiment of FIG. 1 in an attached or assembled condition;

FIG. 3 is a top view thereof;

FIG. 4 is a bottom view thereof;

FIG. 5 is a left side view thereof;

FIG. 6 is a right side thereof;

FIG. 7 is a front view thereof; and,

FIG. 8 is a rear view thereof.

The alternating length broken lines in FIG. 1 show the order of assembly of the exploded view and form no part of the claimed design.
